FIG. 1

FIG. 2

FIG. 3

FIG.5

FIG.4

Fig. 1 is a top perspective view of a composite display and packaging box for watches or the like showing my new design in an open position.

Fig. 2 is a side elevational view thereof.

Fig. 3 is a top plan view of Fig. 1 with the box in a closed position.

Fig. 4 is a rear elevational view of Fig. 3.

Fig. 5 is a fragmentary top plan view on an enlarged scale showing the lower left corner of Fig. 3.

The left side not shown is substantially like the right side shown.

I claim:

The ornamental design for a composite display and packaging box for watches or the like, as shown and described.
